US00D702222S

(12) **United States Design Patent** (10) **Patent No.:** **US D702,222 S**
Kim (45) **Date of Patent:** **** Apr. 8, 2014**

(54) **CASE FOR PORTABLE ELECTRONIC DEVICE**

(71) Applicant: **Samsung Electronics Co., Ltd.**, Suwon-si (KR)

(72) Inventor: **Yoon Young Kim**, Sungnam-si (KR)

(73) Assignee: **Samsung Electronics Co., Ltd.**, Suwon-si (KR)

(**) Term: **14 Years**

(21) Appl. No.: **29/453,918**

(22) Filed: **May 3, 2013**

(57) **CLAIM**

The ornamental design for a case for portable electronic device, as shown and described.

DESCRIPTION

FIG. 1 is a front perspective view of a case for portable electronic device, showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is an enlarged view of the encircled portion 8 as shown in FIG. 6.

In FIGS. 6 and 8, the dot-dash broken line circle indicates the portion of the case that is shown on an enlarged scale in FIG. 8. The other dot-dash broken lines, shown in FIGS. 1, 2, and 8, represent boundaries of the claimed design. All other broken lines depict unclaimed environment. The broken lines form no part of the claimed design.

1 Claim, 6 Drawing Sheets
